NOLLESCHE WERKE ERNST NOLLE, OF WEISSENFELS, GERMANY.

PULLING-OVER MACHINE.

1,110,170.

Specification of Letters Patent.

Patented Sept. 8, 1914.

Application filed April 20, 1907. Serial No. 369,326.

RESCUED

To all whom it may concern:

Be it known that I, HEINRICH WALTRER, a subject of the German Emperor, residing at Weissenfels a. S., in the Province of 5 Saxony and the Kingdom of Prussia, German Empire, have invented certain new and useful Improvements in Pulling-Over Machines, of which the following is a specification.

10 The present invention consists in the combination of a pulling-over machine with an apparatus for binding in of the toe portion of the upper leather as well as in the special arrangement of this apparatus itself. Last- 15 ing machines having only one pair of pincers combined with apparatus for binding in of the toe leather part are already known. But this known combination affords no special advantage, as the binding in is there- 20 by performed in independent operations and at different times from the several other operations of the machine, by means of which the upper is fastened to the insole.

25 In contra-distinction to the combined machines hitherto known in the machine of the present invention the binding in of the toe piece is performed simultaneously with the pulling over operation. Further by the present machine the repeated wetting of the toe 30 piece is obviated, while in the binding in by means of the machines hitherto known the wetted leather is allowed to dry during the lasting operation and has to be wetted again before the binding in takes place. This si- 35 multaneous pulling over of the shoe upper and binding in of its toe part is rendered possible by the automatic binding in apparatus hereinafter disclosed.

40 The present invention relates further to toe-pincers adjustable transversely of the machine and to a device for stopping the nailing during the operation of the machine.

45 In the accompanying drawings Figure 1 shows a side elevation of the machine. Fig. 2 is a horizontal section on the line A—B of Fig. 1, the lower parts of the machine not shown. Fig. 3 shows the hand lever 24 for releasing the toe-pincers. Fig. 4 is a vertical section on the line C—D of Fig. 1 and shows 50 the clutch for operating the machine. Fig. 5 shows a side pincer carrier with the pivot 5 broken away. Fig. 6 illustrates the device for stopping the nailing of the machine. Fig. 7 is a side elevation of the toe pincer carrier. Fig. 8 is a horizontal section on

the line E—F of the Fig. 7. Fig. 9 is a hammer of the toe pincers. Fig. 10 is the binding-in wiper. Figs. 11, 12 and 13 show the binding in wire in the three working stages of the machine.

60 The carrier 1 of the toe pincers is pivotally attached at 2 to the brackets 3 of the machine frame. The carriers 4 of the side pincers rest upon pivots 5 in sockets 6 of the machine. The carriers 4 may therefore 65 be rocked inward and moved along. The pincers consist of a stationary jaw 7 and a movable jaw 8 (see Figs. 5 and 7). The stationary jaws are of one piece with the guiding blocks 9 having sleeves 10 containing the sliding bars 11. These bars are connected on one side by a rack or an equivalent means with the movable jaws, on the other side by links with the frame 12, whereby springs 13 are interposed. The 70 pincers rest by means of springs 14 upon the carriers. The frame 12 works with a roller 15 in a groove 16 of a disk 17 mounted on the driving shaft 18 (see Figs. 1 and 6). In moving down the frame 12 closes at first 75 the pincers normally open and pulls them thereupon down. The pincer carrier 1 is provided with a guide plate 19 for the binding in wiper 20 (Fig. 7). The spring 21 pushes the wiper 20 outward against the 80 set screw 22 of the forked lever 23 pivoted at 2' in the brackets 3.

Before the machine is started the toe part of the upper leather is introduced into the open toe-pincers. In swinging aside lever 90 24 projecting with fingers 25 under the collar 26 of the link 27 the spring 13 comes into action to close the toe pincers and grasp the toe part of the upper, (Figs. 1 and 7). The shoe is then pressed down by hand on 95 to the last rest 36 and held in position by the ball- and heel loops 28 and 29 respectively.

By depressing the treadle 30 the wedge planes 31 on the bar 32 working against 100 wedge planes 33 of a box 34 are actuated and operate to connect the belt pulley 35 with the coupling fastened on the driving shaft 18 and simultaneously disengage by means of the rack 37 the roller 38 placed 105 on the lever 39 from one of the three recesses 40 of a disk pulley 41 (Fig. 4). When the treadle 30 is released the roller 38 slides upon the cylindrical surface of the disk pulley 41 until, owing to the action of the spring 110

42, it automatically engages with the next of the notches 40 stopping thereby the machine at every third of the revolution.

In the first third of the revolution the 5 frame 12 is moved down by the cam-groove 16 to close the side pincers and to grasp the side-margin of the upper, whereupon the side pincers together with the front pincers are simultaneously pulled down.

10 The second working stage begins with the second depression of the treadle. The pincers having grasped and drawn the leather downward the pincer carriers and the binding-in wiper are moved underneath 15 the insole. To do this the pulling over frame 43 is brought into operation. This frame is moved by a groove 44 of the disk 17, into which it projects with a roller 45 on its plate 46 sliding in a vertical guide of 20 the machine. The pincer carriers are drawn by springs 47 against the frame 43, so that the side carriers bear with their inclined shoulders 48 against the rollers 49 of the frame, (Fig. 2), while the tension of 25 the front spring 47 causes by the medium of the spring 21 the forked lever 23 to bear against the rollers 50, (Figs. 7 and 8). The pulling over frame in rising presses the side pincer carriers and the binding-in wiper 30 20 underneath the sole, the wiper moving thereby from the position shown in Fig. 1 into the position shown in Fig. 7.

The binding-in wiper has on either side of its recess suiting the form of the toe 35 part of the last a groove 51 to receive a wire piece as shown in Fig. 11. During the inward movement of the wiper the wire piece assumes the form shown in Fig. 12. The bent wire part embraces the toe part 40 of the leather, while the straight wire parts remain in the grooves 51 which may be dovetailed or otherwise shaped for better guiding of the wire.

At the end of the second working stage 45 the stretched and pulled over upper is fastened by tacks on both sides on to the insole while simultaneously therewith two tacks are driven at the toe part into the insole around which the binding in wire is 50 to be wound as hereinafter described.

In the upper plates 52 of the side pincer carriers 4 (Fig. 5) are arranged tack receiving holes 53 into which the tacks are suitably fed and there are fitted in these 55 holes the drivers 54 fixed on the blocks 55. The latter are guided by rods 56 in the carriers and are connected by bars 57 with the tack driving frame 58, which slides with the plate 59, in guides of the machine frame (Fig. 6). Beneath the frame 58 springs 60 are arranged to act upon the arm 61 which presses by means of the link 62 against the lower part of the plate 59 of the frame 58 which bears with its rollers 63 on the periphery of the cam 17. The

roller 63 entering into the recess 64 of the cam permits the drivers 54 to move upwardly for effecting the tacking. The tacking mechanism of the front pincers differs from those of the side pincers in that the 70 tacks are fed into special nozzles 65 of the wiper 20 in which nozzles the drivers 66 are suspended (Fig. 7). The block 55 has here two arms 67 upon which the drivers 66 slide as the wiper moves in (Fig. 9). The 75 openings of the nozzles and the wire receiving grooves are set to each other in such a manner, that the tacks are driven just between the wire part bent to a loop and the straight parts lying in the grooves 51. The 80 tacks being driven the second working stage is finished.

At the third depression of the treadle the third working stage commences. The stretching frame 12 moves upward and the 85 pulling over frame 43 moves downward, whereby all parts of the machine return to their initial position. The pincers open and move together with the binding-in wiper outward. Owing to the action of the spring 90 68 the lever 24 has already returned with its fingers 25 under the collar 26 of the link 27 in the first working stage as the frame 12 began to compress the spring 13. During the outward movement of the wiper the 95 binding in wire is automatically fastened on the toe tacks not entirely driven in and projecting with their heads from the insole. The edges 69 (Fig. 10) of the groove 51 force the wire under the heads of the nails 100 and wind it around the same. The edges 70 of the groove are beveled to allow the wire to be bent only by the opposite edges 69 and to guide the wire ends to lie next to the formed wire loop. (See Figs. 12 and 13, 105 illustrating these steps.)

To adapt the machine for the manufacture of shoes of different sizes the side pincer carriers are slidably journaled at an inclination to the middle plane of the machine (Fig. 2). The pivots 5 of the pincer carriers 4 are provided with set nuts 71 held in place by bolts 72 projecting into grooves of the nuts. By operating the nuts the side pincers may be longitudinally adjusted with relation to the toe-pincers. The bolts 72 are preferably fastened to a lever 73 by the operation of which the side pincers may be temporarily adjusted with relation to each other, as a buffer arrangement 74 causes the return of the said pincers into their normal position. By this means the toe seam may be righted in case it assumes a wrong position on the last when all the pincers have stretched the leather. It is easily seen that by the adjustment of the side pincers only the toe seam and not the middle line or the back of the upper can be influenced as the pull effected by this adjustment does not tend to draw the 1

leather-back held snugly on the last by the toe pincers. In order to enable the operator to place the leather-back right in case of need, the toe pincers are made according to the present invention adjustable in the direction transversely to the machine.

The part 75 (Figs. 7 and 8) of the toe pincer carrier holding the guiding sleeve 10 is made separately from the carrier-body 10 and slidably hung on bolts 76 of the carrier by means of the side plates 77. A forked lever 78 pivoted on the carrier bears with its arms 79 on the side plates 77 and may be actuated to move the part 75 with the toe pincers to either side thus displacing at will the upper to the right or to the left. If the lever 78 be actuated before the machine is started and after the toe pincers only have grasped the leather it will allow for displacing the upper leather as a whole on the last, while when actuated after all the pincers have taken hold of the upper only the position of the upper may be influenced, as already hereinbefore described. Owing to the action of the spring 13 the toe pincers return to their normal position as soon as they are released in the third working stage.

While the adjustable arrangement of the pincers make it possible to put the upper on the last in the proper position, yet it is sometimes necessary to leave off tacking the leather to the insole and to run the machine to the end of the revolution and then to begin again the pulling over operation on the same shoe. This necessity is experienced for instance, when the margin of the leather slips from one pair of pincers, or when the lining or the counter does not lie smoothly or becomes damaged, which is often noticed in the last moment just before the tacking, when the stretch of the leather is most intense. In such or like cases hitherto the tacking could not be avoided, as all parts of the machine are compulsory driven and after the pulling over operation the tacking takes place. The driven tacks had to be pulled out, the shoe parts again assembled and the pulling over operation repeated. Further in the machines hitherto known the tacks were hereby often driven too far from the margin of the upper and damaged it so that it could not be used any more.

To overcome these difficulties according to the present invention a device is provided by means of which the tacking may be suppressed even in the last moment before it is ordinarily effected. For this purpose a wedge 80 (Fig. 6) may be introduced at any time between the lower part of the plate 59 of the frame 58 and the opposite wall part of the machine frame, against which that plate part comes to lie when the frame 58 owing to the action of the springs 60 enters with its roller 63 the recess 64 on

the periphery of the cam 17. The wedge 80 slides with a guiding bolt 81 in a hole of the machine frame and is held in position on one side by the spring 82 and on the other side by the bent arm 84 of the hand lever 83. By depressing this lever the wedge 80 is forced inward and prevents the tacking frame 58 from going upward and pushing up the drivers. When released the lever 83 bears with a stop 85 against the machine wall.

The present invention discloses several important features. Hitherto no apparatus has been known for binding in of the toe part of the upper without help of the attendant and the principal difficulty which was to be overcome was the automatic fastening of the wire around the tacks. It is apparent that this difficulty is now easily overcome. Also the circumstance that the wiper forces the leather inward while it is being stretched by the toe pincers means an advantage, as the upper is thereby easily pressed under the channel-flap of the insole. The binding in apparatus according to the present invention may as well be built as an independent binding in machine, but it is preferably as shown combined with a pulling over machine of the described or any other type.

It will of course be understood that this invention is not limited to the specific embodiments thereof described and shown in this specification, but that the invention may be embodied in many different mechanical forms and that the several of its features are capable of advantageous use independently of other features.

What I claim is:—

1. In a pulling over machine, a wiper provided with tack receiving holes, pincers journaled beneath the wiper, and means for moving the pincers obliquely with respect to the wiper.

2. In a machine of the class described, tacking mechanism including tack drivers, a wedge movable into position to prevent actuation of the drivers, and a spring acting to normally hold the wedge out of such position.

3. In a machine of the class described, tacking mechanism including tack drivers, a wedge movable into position to prevent actuation of the drivers, a hand lever for moving the wedge, and a spring acting to normally hold the wedge out of such position.

4. In a pulling over machine, a plurality of pincers for gripping and stretching the upper, means for adjusting the pincers longitudinally of the last, a plurality of tack drivers, means for suppressing the operation of the tack drivers while the upper is under tension, to avoid fastening the latter in false position, and a handle for actuating the

means for suppressing the operation of the tack drivers.

5. In a device of the class described, the combination with side pincers, of means for forcibly adjusting the side pincers longitudinally of the last, toe pincers, a toe wiper extending on either side of the toe pincers, tacking means associated with the side pincers, and a plurality of tacking drivers associated with the toe wiper and toe pincers.
6. In a device of the class described, the combination with side pincers, of toe pincers,

a handle for forcibly adjusting the toe pincers along the toe of the last, and means for automatically returning the toe pincers to ¹⁵ their original position.

In testimony whereof I have signed my name to this specification in presence of two subscribing witnesses.

HEINRICH WALThER.
